ABSTRACT: A remote terminal station connected by communication channels to a central processor for the communication of alpha and numeric information. The terminal station is capable of being operated in any one of three independent modes. The first mode is on line with the central processor with an operator entering data into the system at the terminal station. By proper selection of operational keys, the code transmitted by the terminal station is either ASCII or Hamming. The second mode is on line unattended wherein the terminal station "echoes" back to the central processor all information received by it. The third mode is an off-line mode of operation wherein an operator controls the input and output of the station. A recirculating register operating on a time sharing basis is used for synchronizing the operating speed of the terminal station with the speed of transmission over the communication lines.

LEGEND

HAMMING CODE
OVERLAP.

TERMINAL STATION

SUMMARY OF INVENTION

A remote terminal station for the communication of data via communication channels with a central processor. The terminal station includes a keyboard having an alpha section, a numeric section and an operational section for generating a codal representation of the several keys including the operational keys thereon. The codal representation is in either one of two distinct codes depending upon the selection of the operation keys. A recirculating time shared memory is used to buffer the transmitted and received signals between the terminal station and the communication channels.

Each code is processed according to whether it is in ASCII or Hamming. Hamming codes are used in numeric data and are processed through four distinct and different parity operations to determine the correctness of the signal. ASCII codes are processed through one parity operation to determine the correctness of the signal. The selection of parity operations is determined by the actuation of a control member in response to data instructions received thereby from the source of information. Each codal representation of data is composed of the same number of bits arranged into three sub groups.

DESCRIPTION OF DRAWINGS

In the drawings:

FIG. 1 is a diagrammatic illustration of an overall communication system embodying our terminal station;

FIG. 2 is a perspective illustration of the terminal station;

FIG. 3 is a block diagram of the terminal station;

FIG. 4 is a schematic diagram of the basic timing of the terminal station;

FIG. 5 through FIG. 7 are diagrammatic illustrations of the basic timing organization of the terminal station;

FIG. 8 through FIG. 10 are diagrammatic illustrations of the loop organization of the terminal station;

FIG. 11 is a schematic of one stage of a loop;

FIG. 12 is a timing diagram of FIG. 11;

FIG. 13 is a representation of the codes used in the terminal station;

FIG. 14 is a block diagram of the keyboard to loop system;

FIG. 15 is a schematic of the keyboard of FIG. 14;

FIGS. 16 through 18 are schematics of the logic of FIG. 14;

FIG. 19 is the Keyboard State Machine diagram;

FIG. 20 is a Karnaugh map of FIG. 19;

FIG. 21 is a logic schematic;

FIG. 22 is a timing diagram of FIG. 19;

FIG. 23 is the Transmitted Data State Machine diagram;

FIG. 24 is a Karnaugh map of FIG. 23;

FIGS. 25 and 26 are logic schematics;

FIG. 27 is a timing diagram of FIG. 23;

FIG. 28 is the Received Data State Machine diagram;

FIG. 29 is the Karnaugh map of FIG. 28;

FIGS. 30 through 33 are logic schematics;

FIG. 34 is a timing diagram of FIG. 28;

FIG. 35 is the Received Data Parity State diagram;

FIG. 36 is the logic schematic of FIG. 35;

FIG. 37 is a logic schematic;

FIG. 38 is a diagrammatic illustration of printer timing;

FIG. 39 is a timing diagram of FIG. 38;

FIG. 40 is a logic schematic of the C Register and Decoder;

FIG. 41 is the Position Code State Machine diagram and logic schematic;

FIG. 42 is a Karnaugh map of FIG. 41;

FIG. 43 is the Interrupt State Machine diagram;

FIG. 44 is a Karnaugh map of FIG. 43;

FIG. 45 is the Decoder State Machine diagram;

FIG. 46 is a Karnaugh map of FIG. 45;

FIG. 47 is a code chart of the terminal station.

GLOSSARY AND INDEX OF SIGNALS

ASCII, FIG. 47: American Standard Code for Information Interchange; this is the code format for the alpha characters.

BTO FIG. 8: The first bit position in the shift register loops.

BT58, FIG. 39: A special timing bit used in the keyboard input.

BT59, FIG. 14: A special timing bit used in the keyboard input.

BT64, FIG. 4: Special control timing bit used in the basic timing of the terminal station.

BT65, FIG. 4: Special control timing bit used in the basic timing of the terminal station.

CD0 to CD7, FIG. 40: The decoded values of the first three stages of the C register.

C0F to C7F, FIG. 40: The eight stages of the C register. CH_n, FIG. 40: The abbreviation identifying the characters in the recirculating shift registers; *n* is a number from 0 to 7.

CH1F, CH2F, CH4F, FIG. 4: The three stages of the character counter.

CSTK0, CTTK1 and CTTK7, FIG. 40: The decoded signals from the upper three stages of the C register, C5F, C6F and C7F, which identify the particular ASCII code stick, in FIG. 47, of the character in the C register.

CT_n, FIG. 4: The abbreviation identifying the bits in each character of the recirculating shift registers; *n* is a number from 0 to 7.

CT1F, CT2F, CT4F, FIG. 4: The three stages of the bit counter.

CXT: A command signal as used in the overall system having the meaning "execute" and refers to the signals stored in the C register.

CXTT, FIG. 40: A command signal as used in the overall system having the meaning "execute timed" and refers to the signals stored in the C register.

DS0 to DS7, FIG. 45: The several states of the Decode State Machine.

DSF1, DSF2, DSF4, FIG. 46: The state control flip-flops of the Decode State Machine.

EC1, EC2, EC3, EC4, FIG. 35: The several states of the Received Data Parity Check.

Echo Back, FIG. 14: The serial output of the C register for transmission to the central processor during the on line unattended mode of operation.

ENCXT, FIG. 40: A command signal as used in the overall system having the meaning "enable execute" and refers to the signals stored in the C register.

Error: A control signal identifying the error conditions required to set the error flag in BT65 of Loop zero.

FND BIT, FIG. 18: The signal identifying a particular bit position of the keyboard output for loading into the keyboard buffer.

Group A, Group B, Group C, FIG. 13: The designation of the three groups of pulses generated by the keyboard.

Hamming: The code format used for the numeric characters from the numeric keyboard.

HF, FIG. 40: The signal identifying the true side of the Hamming control flip-flop.

Initialize, FIG. 19: Initial power on sequence setting the several state machines of the terminal station in state zero.

INTRPT, FIG. 43: The output signal generated from the interrupt key.

IP2F: The control flip-flop for the program select key No. 2.

IP3F: The control flip-flop for the program select key No. 3.

IS0 to IS3, FIG. 43: The several states of the Interrupt State Machine.

ISF1, ISF2, FIG. 44: The state control flip-flops of the Interrupt State Machine.

KBDFF, FIG. 14: The keyboard control flip-flop controlling the loading of information into the keyboard buffer.

KBL1, KBL2, KBL4, KBL4, KBL8, FIG. 15: The Group A output signals from the keyboard.

KBST, FIG. 15: The keyboard strobing signal.

- KBU1, KBU2, KBU4, FIG. 15: The Group B output signals from the keyboard. 5
- KBU8, FIG. 15: The Group C output signals from the keyboard and in particular the shift key output signal. 5
- KCLFF, FIG. 21: The keyboard clock flip-flop used as a modulus 2 binary counter. 5
- KCLK, FIG. 21: The keyboard synchronized clock signal. 10
- KF, FIG. 37: The output signal from the keyboard-line flip-flop. When this signal is true, the information in the C register was received from the input buffer, and when false, the information was received from the keyboard buffer. 10
- KSO to KS7, FIG. 19: The several states of the Keyboard State Machine. 15
- KSER, FIG. 14: The output signal of the serializer. 15
- KSF1, KSF2, KSF4, FIG. 20: The state control flip-flops of the Keyboard State Machine. 15
- KSTK6, KSTK67, FIG. 16: The decoded signals in the keyboard decoder, of the Group B pulses identifying the particular ASCII code stick of FIG. 47. 20
- Loop Zero, Loop One, Loop Two, FIGS. 8, 9 and 10, respectively: The three 66 bits recirculating shift registers used for information storage within the terminal station. 25
- L0R, FIG. 18: "Loop Zero Read," when true, indicates the presence of information in a particular stage of Loop Zero. 30
- L0W: "Loop Zero Write." 30
- L1R, FIG. 28: "Loop One Read," when true, indicates the presence of information in a particular stage of Loop One. 30
- L1W, FIG. 41: "Loop One Write." 35
- LSB, FIG. 47: Least significant bit. 35
- LSD, FIG. 47: Least significant digit. 35
- LSES01, FIG. 36: This signal, when true, controls the parity checking logic for the received data. 35
- MSB, FIG. 47: Most significant bit. 40
- MSD, FIG. 47: Most significant digit. 40
- $\phi_1\phi_2$, FIG. 4: The clocking signals used to internally shift the 66-bit recirculating shift registers. 40
- ONLU FIG. 40: On line unattended, a mode of operation of the terminal station. 45
- POF, FIG. 18: The control flip-flop signal associated with character zero of the keyboard buffer indicating when character zero is full. 45
- P1F, FIG. 18: The control flip-flop signal associated with Character one of the keyboard buffer indicating when character one is full. 50
- P2F, FIG. 18: The control flip-flop signal associated with character two of the keyboard buffer indicating when character two is full. 50
- P0FF, P1FF, P2FF, FIG. 18: The control flip-flops associated with POF, P1F, and P2F, respectively. 55
- PERR, FIG. 35: The signal identifying that the received character has a parity error. 55
- PF30T, FIG. 39: Printer timing control clock. 55
- PM0 to PM3, FIG. 41: The several states of the Position Code State Machine. 60
- PMF1, PMF2, FIG. 42: The state control flip-flops of the Position Code State Machine. 60
- POS, FIG. 40: A command signal as used in the overall system having the meaning "position" and refers to the printing position of the printer. 65
- POSXT, FIG. 40: A control signal as used in the overall system having the meaning "position execute" and refers to the signals stored in the C register. 65
- PSO, FIG. 43: The control signal identifying that all three characters of the keyboard buffer are empty. 70
- RCADATA, FIG. 30: The data signal identifying information received from the transmission line. 70
- RCDF, FIG. 3: Received data flip-flop. This flip-flop temporarily stores the RCADATA signals until they are loaded into the input buffer. 75
- RCL1, RCL2, RCL4, RCL8, and RCLA, FIG. 30: Modulus 32 counter for generating the synchronizing clock for the Received Data State Machine. 75
- RCLK, FIG. 28: The receive data synchronizing clock signal. 75
- RPF, FIG. 36: The received parity flip-flop. 75
- RS0 to RS15, FIG. 28: The several states of the Received Data State Machine. 75
- RSF1, RSF2, RSF4, RSF8, FIG. 29: The state control flip-flops of the Received Data State Machine. 75
- SCL1, SCL2, FIG. 32: Modulus 4 counter for generating the sampling clock. 75
- SCLK, FIG. 28: Sampling clock signal as used in the Received Data State Machine. 75
- SHIFT, FIG. 14: Keyboard control signal for changing the output characters of the keyboard from lower case to upper case. 75
- SI, FIG. 14: The command identifying all subsequent signals as being in the ASCII code format. 75
- SKCXT, FIG. 45: The command meaning "skip C execute." 75
- SMO: The control signal indicating that several particular state machines are in state zero. 75
- S ϕ , FIG. 14: The command identifying all subsequent signals as being in the Hamming code format. 75
- SY40, FIG. 45: A control signal identifying that all printer movements have been completed. 75
- SYM, FIG. 45: A control signal identifying that all printer functions have been executed. 75
- T, FIG. 4: The basic timing clock signal of the terminal station. 75
- TBF, FIG. 26: Transmit buffer flip-flop which temporarily stores information during transmission on the telephone lines. 75
- TCF, FIG. 31: Timing count pulse flip-flop signal which is used in printer timing. 75
- TCL1, TCL2, FIG. 25: Modulus 4 counter for the transmit clock. 75
- TCLK, FIG. 25: The transmit data synchronizing clock signal. 75
- TEN, FIG. 23: Transmit enable signal to initiate the Transmit Data State Machine. 75
- TPF, FIG. 26: Transmit parity generator flip-flop. 75
- TS0 to TS7, FIG. 23: The several states of the Transmit Data State Machine. 75
- TSF1, TSF2 and TSF4, FIG. 24: The state control flip-flops for the Transmit Data State Machine. 75
- TUF, FIG. 38: Timing unit flip-flop signal which is used in printer timing. 75
- WT n , FIG. 4: The word unit of data equal to 66 bits; n is a number from 0 to 7. 75
- XFRFF, FIG. 18: The transfer flip-flop which is used as temporary storage for data being transferred from character to character within the keyboard buffer. 75

DETAILED DESCRIPTION

System Description

- 60 Referring to FIG. 1 there is illustrated in diagrammatic form an overall system wherein the terminal station of the present application is one part. Such a system may be used in applications such as that of branch banking wherein the central data processor 100 is located at the main bank computing center and is connected by telephone lines 102 to the terminal stations 104 located at branch banks. The central data processor 100 is a computer such as the Burroughs B5500, which is capable of receiving information in various forms such as on punch paper tape 106, punch card 108, and magnetic tape 110. Connected to the central processor 100 are a plurality of central modems 112 which provide an interface between the central processor and the telephone lines 102. At the other end of the telephone lines 102 are terminal modems 114 which are similar in construction and operation to the central modems 112. 75

Each terminal modem 114 is associated with a time division multiplexer 116, hereinafter referred to as a TDM, which has the capability to control telephone lines 102 in a full duplex mode of operation.

For purposes of illustration, FIG. 1 represents a system utilizing the second modem channel. Attached to the TDM No. 2, each by a separate telephone line 102, are terminal stations 104 such as those shown, which are interfaced to the telephone lines by line adapters 118.

In order to effect communication between any one terminal station 104 and the central processor 100, the central processor polls each of the central modems 112 until it receives a signal indicating that a particular terminal station 104 is ready to go on line. Upon completion of the poll, a particular terminal station is then operatively connected to the central processor 100 for transmission and reception of information.

Referring to FIG. 2, there is illustrated the terminal station 104 used in the overall system of FIG. 1. Each terminal station has a typewriter keyboard 120 comprising an alpha 122 and a numeric 10-key keyboard 124. In a bank operation, for instance, all amount figures and possibly account numbers would be entered into the numeric keyboard 124 whereas such information as name, address, or other designations would be entered into the alpha keyboard 122. To provide effective communication between the operator and the terminal station 104 a plurality of program select keys 126, PSK, and indicator lamps 128 are provided rearward of the keyboard to indicate the operating mode of the terminal station. As will be hereinafter shown with such a terminal station 104, the operator will be able to effect data communication with the central processor 100 and simultaneously will have a visible printing record of the communication.

In FIG. 3 there is shown a block diagram of the organization of the terminal station shown in FIG. 2. The keyboard 120 comprises both the alpha keyboard 122 and the numeric keyboard 124. Information indexed on the keyboard 120 is converted directly into ASCII and Hamming codes prior to being transferred in parallel to the keyboard decoder 130 for conversion from lower case to upper case characters. The keyboard decoder 130 has seven parallel outputs which are operatively coupled to the serializer 132 wherein the code is converted to serial form. The information, now in serial form, is stored in the keyboard buffer 134 until it is transmitted.

The transmit control 136 in combination with the parity generator 138 and the transmit buffer 140, operate to convert the data from its high frequency representation of 230 kHz. as stored in the keyboard buffer 134 to the low telephone transmission frequency of 110 Hz. The information in the transmit buffer 140 is converted by a data level shifter 142 into the voltage levels of transmission which are supplied to the line adapter 118.

Information received from the telephone lines 102 by the line adapter 118, is converted by a data level shifter 144 into the voltage levels of the terminal station 104 and then is stored in the received data flip-flop 146, RCDF. The receive control unit 148 synchronizes the output of the RCDF 146 with the basic timing of the terminal station 104 and stores the information in the input buffer 150. The parity check unit 152 then determines the correctness of the information in the input buffer 150 and then the signals are serially loaded into the C register 154 for processing. If the contents of the C register 154 represent operational information, the C register 154 is decoded by the register decoder 156 and applied in parallel to the control matrix 158 for the generation of the appropriate operation signal. If the contents of the C register 154 represent data information which is to be printed out by the terminal station 104, the C register 154 is connected in parallel to the printer 160.

In the system illustrated in FIG. 1, each terminal station 104 may be operated in one of three modes of operation. The first mode is an off-line mode wherein any information entered into the keyboard 120 will be printed out by the printer 160 and not be transmitted. Referring to FIG. 3, the information entered by the keyboard 120 in this mode of operation is

transferred from the keyboard buffer 134 via conductor 162 to the C register 154. In the second mode of operation, the terminal station 104 is connected on line with the central processor 100 in an unattended mode of operation. In this mode, the central processor 100 transmits operational and data information to the terminal station 104 for print out by the printer 160 and receives back, in echo fashion, the transmitted information from the terminal station. In FIG. 3, this mode of operation is shown by the connection from the C register 154 via conductor 164 to the input of the keyboard buffer 134. In the third mode of operation, the terminal station 104 is connected in online mode wherein the information is entered into the system by the operator at the terminal station, transmitted to the central processor 100, and receives data in response thereto from the central processor.

Timing Organization

General Data

Referring to FIGS. 5, 6 and 7, there is illustrated in descending order the basic timing organization of the data flow within the terminal station 104 of FIG. 3. The basic unit of data is the bit 166, which is identified by signal CT_n, where "n" represents a number from 0 through 7. A character 168, the next order of data, is identified by the sign CH_n and is comprised of eight bits, with CT0 as the least significant bit. The subscript "n," in CH_n represents a number from 0 through 7. The third order of information is the word WT_n, where n represents a number from 0 through 7. A word is comprised of 66 bits: eight characters 168 plus two bits, BT64 and BT65. BT64 and BT65 are unique bit positions having several functions and will be explained hereinafter.

A keyboard frame 172 is the highest order of information and is comprised of eight words, WT0 through WT7. This unit is used primarily in the interrogation of the keyboard 120. Particular bit times in a word are identified by either the label CH_n CT_n or by bit position counting from bit 0. Two such times are bit time 58, BT58, and bit time 59, BT59, which correspond to CH7, CT2 and CH7, CT3, respectively.

Basic Clock Generation

In the system of FIG. 3, there are four basic clocking pulses which are used in the logic elements of the system; namely, phase 1 (Φ1) 174 and phase 2 (Φ2) 176, basic timing clock T 178, and printer timing clock PF30T 180 which is shown in FIG. 38. The basic timing clock T 178 has a pulse repetition frequency of approximately 232 kHz. and a pulse width of approximately 0.6 microseconds. This clock 178 is used in processing signals in the terminal station. The phase clocks, Φ1 and Φ2, are used in the recirculating shift registers in a manner to be hereinafter explained. The signal PF30T 180 is used to synchronize the logic signals with the much slower operations of the mechanical sections of the terminal station 104.

All of the previously enumerated clocking signals are originated from a crystal oscillator 182 having an oscillation frequency of approximately 1900 kHz.

Referring to FIG. 4, there is schematically illustrated the logic modules used to generate the basic clocks and the basic data organization signals.

Phase Clocks, Φ1 and Φ2

As shown in FIG. 4, phase 1, Φ1 174, and phase 2, Φ2 176, clocks are generated from the crystal oscillator 182. The output of the oscillator 182 is divided by a 3-stage flip-flop counter 184 FF1, FF2, and FF4. This divides the frequency of the clocks from 1900 kHz. to 232 kHz. The outputs of the flip-flops are combined in two separate AND gates 186 and 188 to provide the phase clocks according to the following equation:

$\phi 1=FF1\cdot FF2/FF4$

$\phi 2=FF1\cdot FF2/FF4/$

These two clocks 174 and 176 are only used in the recirculating shift registers and as shown in FIG. 12, the clock pulses actually used are the inverted phase clocks as generated above.

Basic Timing Clock, T

Referring to FIG. 4, the output of the oscillator 182 is divided by eight in a 3-stage counter 184. The several outputs of the counter are decoded in the oscillator decoder 185 into discrete outputs one of which is the basic timing clock, T 178. This is the basic timing pulse which has a pulse width frequency of 928 kHz. and a pulse repetition frequency of approximately 232 kHz. or one-eighth of the oscillator frequency. As illustrated in FIG. 4, all of the basic timing measurements are generated from the basic clock signal, T 178.

This signal, T, is gated via an AND gate 190 into the input of a 6-stage ripple counter 192. Each stage of the counter is a JK flip-flop 194 connected in the well-known manner for ripple counters. Each stage is actuated from the resetting of the previous stage and if all six stages were decoded, the counting output would be from 0 to 63.

The 6-stage counter 192 is divided into two sections 196 and 198; namely, stages 1 to 3 and stages 4 to 6. The first section 196 comprising CT1F, CT2F, and CT4F is decoded in a binary to octal decoder 200 to provide the discrete bit pulses CT0 to CT7.

The second section 198 comprising CH1F, CH2F and CH4F is decoded in a similar manner by a binary to octal decoder 202 to provide the discrete character pulses CH0 to CH7. As previously mentioned, the carry from CT4F is the trigger or count signal to the second section 198.

After the 63rd pulse, both sections of the 6-stage counter 194 are fully loaded giving a count equal to 63 decimal or 77 octal and a decoded count of CH7 CT7. The next timing pulse T is gated via a second AND gate 204 to set BT64F 206 and also via the first AND gate 190 to count the 6-stage counter 194. After the 64th pulse, the 6-stage counter is equal to 0 or CH0 CT0 and BT64F 206 is true. The next timing pulse resets BT64F and sets BT65F 208 true and the counter remains at CH0 CT0. The 66th timing pulse resets BT65F 208 with CH0 CT0 still remaining true. Thus CH0 and CT0 have remained true for three clock periods. To provide better logic control and to give the proper timing value to CH0 and CT0, these signals are further decoded so as to appear only at the beginning of the operation and every 66th pulse thereafter. The following equation defines CH0 and CT0 which are the logic signals used throughout the machine in terms of CH0A and CT0A which are three clock periods long:

$$CH0=CH0A\cdot BT64F\cdot BT65F/$$

$$CT0=CT0A\cdot CH0$$

The resetting of BT65F 208 counts a second 3-stage ripple counter 210 which counts the third order of information of the terminal station 104 which is the word 170. This counter 210 is a modulus eight counter which is decoded in a third binary to octal decoder 212 to provide the eight discrete word pulses WT0 to WT7.

Printer Timing Clock, PF30T

The fourth basic clock signal is derived from the continuously rotating shaft 214 in the printing section of the terminal station 104 as illustrated in FIG. 38. The waveforms of FIG. 39 show the timing derivation of signal PF30T 180 which is one bit time wide.

In the terminal station 104, the shaft 214 which is driven by the terminal station motor 216, rotates at 1200 r.p.m. which gives a revolution time of 50 milliseconds. To generate a timing signal from the shaft 214, a disc or cam 218 and a

photocell network 218 may be employed as shown in FIG. 38. The "dark" portion 220 of the disc is the sector labeled 30T to 03T and the "light" portion 222 of the disc is the sector labeled 03T to 30T. The output of the photocell 224 is amplified 226 and gated via the two input AND gates 228 to the J terminal of a JK flip-flop 230 TUF. The second input of the AND gate 228 is a unique bit time signal, BT59. On the immediately preceding bit time, BT58, the K input is true and the TUF flip-flop 230 is reset. This is shown in FIG. 39 where the signal TUF 232 is interrupted every 66th pulse. If the output of the photocell is "one" which is between 30T and 03T, then TUF is true except for the time between BT58 and BT59.

As shown in FIG. 31, the setting conditions for TCF flip-flop 234 is as follows:

$$TCF=BT65\cdot TUF$$

and the resetting of TCF is as follows:

$$TCF=CT7b\cdot TUF/$$

Thus, the only difference between TCF and TUF is that TCF is a steady signal 236 without any discontinuities. Both flip-flops have the same overall time period but are displaced by five timing pulse times.

PF30T 180 is a signal which is generated at the beginning of the "light" sector 222 of the disc 216 or at essentially 30T time. The equation for PF30T is:

$$PF30T=BT65\cdot TUF\cdot TCF/$$

Indicators and Program Keys

Referring to FIG. 2, there is illustrated directly above the numeric keyboard 124, a set of eight program select keys 126 each having an indicator light 128 above them.

Depression of any program select key will generate an 8-bit ASCII code signal which will be transmitted to the central processor 100 and when that signal is received by the central processor it will acknowledge receipt by transmitting a signal to turn on the indicator lamp associated with the particular program select key which is depressed.

The terminal station 104 of the present embodiment, has two program keys and associated indicators which allow and acknowledge the change of mode of operation. The following chart identifies the three modes of operation of the terminal station in terms of two flip-flops; namely, IP2F and IP3F which are associated with program select keys 2 and 3.

	Mode:	Flip Flop Status
50	On line attended.....	IP2F/·IP3F/
	On line unattended.....	IP2F/·IP3F
	Off line.....	IP2F

The other program select keys may be used for whatever function is desired and will vary with each application of the terminal station 104.

Loop Shift Register
FIGS. 8, 9, and 10 238, the organization of each of the three recirculation loops 238, 240 and 242 used in the terminal station 104. Each loop is a dynamic 66-bit shift register wherein each stage 244 is serially connected via its input and output to the adjacent stages. The 66 stages are further subdivided into eight sections or characters CH0 through CH7 of eight stages or bits each CT0 through CT7 plus two discrete bits BT64 and BT65.

FIG. 11 depicts the configuration of a typical stage 244 of each loop. Each stage is operatively divided into an input section and an output section. Information is admitted into the input section by the phase one clock pulse $\phi 1$ 174 and is transferred to the output section by the phase two clock pulse, $\phi 2$ 176.

In the preferred embodiment, each stage comprises six MOS insulated gate field effect transistors, Q1 through Q6. The first three transistors Q1 246, Q2 248, and Q3 250 are

used in the input section; and the remaining three transistors Q4 252, Q5 254, and Q6 256 are used in the output section. The first transistor in each section, namely, Q1 and Q4, function as transfer gates, the second transistors in each section, Q2 and Q5 function as inverters and the third transistors Q3 and Q6 function as the load resistors for each inverter. The two capacitors which are illustrated as C1 258 and C2 260 represent the parasitic capacitance of each section and it is this capacitance which temporarily stores the information in each section.

The waveform of FIG. 12 shows the relationship between the several transistors and the three clocking signals, T, ϕ_1 and ϕ_2 . The first waveform, T 178, represents the basic clocking signal of the terminal station 104 and the next two waveforms represent the phase clocks ϕ_1 174 and ϕ_2 176 which are derived therefrom. The function of ϕ_1 is to transfer information into the input section and the function of ϕ_2 is to transfer information from the input section to the output section.

The waveform labeled Point A, depicts an information bit as it appears at the input A of the input section. Since the logic of the terminal station 104 is positive logic, i.e., binary "1" is represented by +5 volts and binary "0" is represented by 0 volts, the information being transferred into the loops must be inverted; therefore, the waveform Point A represents binary "1." At ϕ_1 the input signal is transferred to Point B by driving the first transistor Q1 into conduction. With Q1 conducting the capacitance C1 is charged through the transistor Q1 to the negative potential of the input signal. When C1 becomes charged, the inverter transistor Q2 is driven into conduction causing Point C to approach ground potential. At the termination of ϕ_1 , the input transistor Q1 is driven out of conduction but the negative charge on C1 keeps Q2 in conduction. Since the leakage current in these devices is extremely small, transistor Q3 will remain in conduction for a period of time much greater than the interval between successive phase clocks.

Phase 2 clock, ϕ_2 , which controls the output sections of the stage, drives the second transfer transistor Q4 into conduction to initiate transfer of the input data to the output section. The capacitance C2 charges to the ground potential of the signal at Point C thereby driving the second inverting transistor Q5 into conduction lowering the voltage at Point E to approximately ground. At the termination of ϕ_2 , the transfer transistor Q4 is driven out of conduction and the information signal, represented by the waveform Point A has thus been transferred from the input section at Point A by ϕ_1 to the output section at Point B by ϕ_2 , which is represented by the waveform Point E.

On Line Unattended

As previously mentioned under System Description, the terminal station 104 may operate in one of three different modes. As identified therein, one of the modes is an on line unattended operation. In this mode, the terminal station 104 is under the complete control of the central processor 100. The central processor, by appropriate commands, can turn the terminal station motor 215 on or off, cause the terminal station 104 to print out information or do any other function which could be accomplished in either of the other two modes, except, of course, entering data into the system via the keyboard 120.

Referring to FIG. 3, in the on line unattended mode of operation, the data flow is the same as for all other modes with the following exceptions. First, the keyboard entry system as herein described is not used and second, the contents of the C register 154 is transmitted back to the central processor 100 as indicated by the conductor 164 in FIG. 3.

In FIG. 40, the output of the AND gate 262 labeled ECHO BACK is shown in FIG. 3 as the conductor 164 to the OR gate 264 at the input to the keyboard buffer 134. This is also illustrated in FIG. 14.

To insure reliability of remote operation, all signals, which may be either data or commands or both, which are received by the terminal station 104 from the central processor 100 are

"echoed back" to the central processor. In this way the central processor 100 can compare the signal which it sent to the terminal station with the echoed back signal to determine if any error has been introduced in the system. If an error has been introduced, the central processor can then initiate the desired error correcting sequence.

To put the terminal station 104 on line in an unattended mode, the terminal station must be turned on but the printer motor 215 need not be running. In this condition, the terminal station 104 is prepared to receive signals from the central processor. As previously mentioned, the central processor 100 can transmit a command to turn the printer motor 215 on. Likewise, when the central processor has completed its transmittal of information, it will then turn the printer motor off.

In FIG. 40, the echo back signal is generated by a four input AND gate 262. One input is the output of the C register 154; namely, stage C0F 266. This is a serial output of the C register since transmission is in bit serial coded format. The second input is ONLU 268, on line unattended signal, which is controlled by a program select key 126 depression by an operator and is further indicated on the terminal station by an indicator light 128. The third input DS2 is the state machine control. This state is true for one word time which is sufficient to transfer the contents of the C register 154 to the keyboard buffer 134 prior to transmission. The fourth input is the character time corresponding to the first section of the keyboard buffer 134; namely, CH0, as illustrated in the loop 0 organization chart of FIG. 8. The C register is shifted by gate 269.

In order to place the terminal station 104 in the on line unattended mode of operation, the operator transfers the ONLU program select key which is positioned above the keyboard 120 as shown in FIG. 2 to the on position. The transfer of this key turns on an indicator lamp and also sets a control flip-flop IP3F true. To be unattended, the operator transfers the type program select key to the off position which controls another control flip-flop IP2F. Thus the signal ONLU 260 is generated according to the following equation:

$$\text{ONLU} = \text{IP2F} / \text{IP3F}$$

Once the above conditions are set, the terminal station 104 is under the complete control of the central processor 100. If the operator decides to regain control she must proceed through an interrupt program which basically requests the central processor to relinquish its control over to the operator.

Decode State Machine

The Decode State Machine is the main control state machine for the terminal station 104. The several other state machines take their control from particular states of this state machine.

The Decode State Machine is controlled by three flip-flops which are DSF1, DSF2 and DSF4. The outputs of these three flip-flops are gated together to provide several discrete decimal values from 0 to 7 which determine the particular state of the state machine diagram of FIG. 45. The functions of the several states are enumerated in the table below with the status of the three flip-flops as shown in the Karnaugh map of FIG. 46.

State	Status	Flip Flop	Function
DS0.....	000		Initial State.
DS1.....	001		Wait for PF30T to executive code in C register.
DS2.....	010		Prepare for C register execute.
DS3.....	011		Load C register.
DS4.....	100		Execute Printer Operations.
DS5.....	101		Not used.
DS6.....	110		Execute code in C register.
DS7.....	111		C register parity check.

In FIG. 45 upon applying power to the terminal station, the initializing routine sets the state machine to state zero as identified by DS0 270. The state machine remains in DS0 until

data is available either in the input buffer 150 or in the keyboard buffer 134 for processing. If the data to be processed is coming from the input buffer 150, the state machine will progress from DS0 270 to DS7 272 according to the following equation:

$$DS7 = LOR(BT64 \cdot WT3)$$

As shown in FIG. 8, bit 64 of loop zero 238 will have a binary 1 bit if there is information in the input buffer 150. Thus, during word time 3, if loop zero is read at BT64 and a binary 1 bit is present, the Decode State Machine will progress to DS7 272. During the time that the state machine is in DS7 a parity check is performed on the data which is in the input buffer 150. The parity check routine is hereinafter discussed with the received data parity check section in conjunction with FIG. 35. If a parity error is found, a signal PERR 274 is generated indicating that there is a parity error in the input buffer 150 and the Decode State Machine is returned to DS0 270. If there is no parity error, the state machine progresses to DS3 276.

As shown on the above table, the function of state DS3 is to load the C register 154. As shown in FIG. 3, the C register 154 is loaded from either the input buffer 150 or from the keyboard buffer 134. As previously stated, prior to processing the data from the input buffer, a parity check is performed in DS7 272; but, if the information to be loaded into the C register is in the keyboard buffer 134, no parity check is performed. In this case, the state machine progresses from DS0 270 to DS3 276 according to the following equation:

$$DS3 = ISO \cdot IP2F \cdot P2F \cdot BT65$$

where ISO indicates the initial state of the Interrupt State Machine, IP2F indicates that the load of the terminal station 104 is off line, and P2F indicates that there is data in CH2 of the keyboard buffer 134. When the above conditions are met, the state machine will progress to DS3 at BT64. An additional condition for changing from state DS0 or DS7 to DS3 is WT7. The combination of WT7 and BT65 will cause DS3 to begin at WT0, CH0, and CT0.

The state machine remains in DS3 276 until the end of CH5 or for six character times. During character time two, CH2, the information from the keyboard buffer 134 is loaded into the C register 154. During character time three, CH3, the information from the input buffer 150 is loaded into the C register 154. The controlling flip-flop for loading the C register in the above operations is the KFF or keyboard flip-flop 278. As shown in FIG. 37, this flip-flop is set depending upon whether information is in the input buffer 150 or not. The signal which causes the state machine to progress from DS0 to DS7 resets the keyboard flip-flop 278 indicating that the C register is to be loaded from the input buffer 150 during CH3 time; the signal which causes the state machine to progress from DS0 to DS3 sets the keyboard flip-flop 278 indicating that the C register is to be loaded from the keyboard buffer 134. At time CH5 CT7 the state machine progresses from DS3 to DS2.

As mentioned in the above table, during DS2 280 time several circuits and functions within the terminal station 104 are being prepared according to various commands received by the terminal station. The state machine remains in DS2 for one word time or until CH5, in WT1. Depending upon where the information in the C register 154 originated and also depending upon the type of information in the C register the state machine will progress from DS2 280 to either DS0 270, DS1 282, or DS6 284. If the information in the C register is decoded as SKCXT, which is skip C execute, the machine will return to DS0 at CT0 time. If the information originated in the keyboard buffer 134, the state machine will progress to DS1 282 at CT7 time. If the information originated in the input buffer 150, the state machine will progress to DS6 284 at CT7 time.

The next three states DS1 282, DS6 284, and DS4 286 control the execution of the information within the C register.

State DS1 282 is a synchronizing state which synchronizes the Decode State Machine with the printer 160 operation. As indicated in the table above, and as shown in FIG. 45, we will remain in DS1 until the printer timing signal PF30T 180 is generated. However, if during the time we are in DS1, information is being processed by the Receive Data State Machine, and if that machine is in states 4, 8, or 12, the Decode State Machine will return to DS0 270. During DS6 the information in the C register is executed. If the command relates to a printer operation, a signal SYM is generated which will cause the state machine to go to state DS4. If the information does not relate to a printer operation, the state machine will return to DS0. The timing signal for either operation is WT7 and BT65. The state machine remains in DS4 until a signal is received from the printer 160 indicating that the operation is complete. This signal, SY40, then causes the state machine to return to DS0. The signal SY40 indicates that the printer 160 has finished its movement and any shifting of the ribbon from either red to black or black to red has been completed. As previously mentioned, the Decode State Machine is the fundamental state machine within the terminal station 104 and from it several other state machines receive their timing.

Keyboard Input

As illustrated in FIG. 2, the terminal station which may be used in the overall system of FIG. 1, has a keyboard 120 for the manual entry of information into the system. The keyboard is comprised of two main sections; namely, an alpha section 122 and a numeric section 124 each having, in addition to keys normally associated with each section, several operational keys. Three operational keys which are of particular importance are identified as SO 288, SI 290, and SHIFT 292.

In the preferred embodiment, the keyboard mechanism is comprised of seven code slides which collectively cooperate to generate a positionably coded 7-bit code for each key, a shift slide, and a self-generated strobing signal. The alpha keyboard 122 has the general appearance and operation similar to that of a standard typewriter keyboard in that each key has two distinct output values. The first value, which is the normal output, is a lower case letter or symbol and the second value is an upper case letter or symbol. In order to change the output from the normal lower case to the upper case output, the SHIFT key 292 must be simultaneously depressed with the desired information key. In the standard ASCII code, this key changes the bit configuration of the bits 4 through 6 or the Group B bits 294 of FIG. 13.

The SO 288, shift out, and SI 290, shift in, keys are depressed when the operator desires to go from one keyboard such as the alpha keyboard 122 to the second keyboard or the numeric keyboard 124. Since, as illustrated in FIG. 13, and FIG. 47, the codal representation of some letters such as a "C" and numbers such as a "3" are identical, some further identification must be made in the system to separate the numeric from the alpha. In the present embodiment, this is accomplished by the depression of either the SO and SI keys 288 or 290.

Referring to FIG. 47, there is illustrated in chart form the codal relationship between alpha and numeric characters of the standard 7-bit ASCII code and the numeric characters of the Hamming code. Alpha and numeric characters which are generated by depression of the keys in the standard alpha or typewriter keyboard, are generally used in transactions wherein an improper character is easily identified or basically not harmful as far as the data is concerned; hence, only a full character parity check is made with the resulting parity bit positioned in Group C 296 as illustrated in FIG. 13. In the ASCII code, all of the bits in Group A 298 and Group B 294, which are seven in number, are used as binary information bits. The Group C 296 bit from the keyboard 120 is the codal representation of the shift key 292. This bit is later replaced, as will be shown in the Transmitted State Machine, with the above mentioned parity bit.

If the indexed character is from the numeric keyboard 124, the codal representation is also seven bits, but as illustrated in FIG. 13, the Group A 298 bits, which in this embodiment are four in number, are the information bits and the Group B 294 bits, which are three bits, are the group parity bits. This codal representation is referred to as the Hamming code. In the Hamming code, the fourth, fifth and sixth bits are even parity bits for particular combinations of the information bits zero through three according to the following table:

Information Bits	Group Parity Bits	Character Bits
Group A	Group B	Group C
0 1 2 3	4 5 6	7
X X X	X ..	-----
X X X	.. X ..	-----
X X ..	 X	X
X X X ..	.. .. ..	-----

In the Hamming code as used herein, the Group C 296 bit, is both the group parity bit and the character parity bit.

The SI key 290 generates a 7-bit code, in the same manner as any other key on the keyboard. The only difference is that this code indicates to the central processor 100 that all subsequent codes are in the ASCII format. The SO key 288 likewise generates a 7-bit code but to the central processor 100 this code indicates that all subsequent codes are in Hamming code.

When any key in either keyboard 122 or 124 is depressed, the action of the seven code slides is indicated by a series of seven transducers 300, one for each slide, which provide either one of two outputs which are further decoded in the familiar "1" or "0" binary output. In order to determine when a particular key is ready to be read out of the keyboard 120, a keyboard strobing signal KBST 302 is generated to provide a signal at a time when all the seven slides in the keyboard are fully actuated. This signal, KBST 302, provides a mask for the proper and safe interrogation of the several transducers.

The information from the keyboard 120 is then decoded and if the shift key 292 was depressed, the information from the keyboard is altered as previously explained. At this point in the data flow, the information is being processed in bit parallel form but in order to communicate with the central processor 100, the information must be in bit serial form. Therefore, the information from the decoder 130 logic is transferred to a serializer 132 where it is changed from bit parallel to bit serial flow. The output of the serializer, KSER 304, is then fed via a special control member, KBDFF 306, into the keyboard buffer 134 which is identified as loop 0, character 0 under control of the Keyboard State Machine.

Referring in detail to FIGS. 14, 15, 16 and 17, the logic diagrams for the transfer of information from the keyboard 120 to the keyboard buffer 134 are shown. FIG. 18 illustrates the logic necessary for the transfer control 308 which is illustrated in diagrammatic form in FIG. 14.

For the purpose of illustration, the logic will be described for the transmission of an upper case "C." For the purpose of the keyboard to keyboard buffer system, the type of code used is immaterial as the selection of either the SO 288 or SI 290 keys will identify the code being used to the central processor 100.

In FIG. 15, the binary output of keyboard is indicated on the lines KBL1, KBL2, KBL4, KBL8, KBU1, KBU2, KBU4 and KBU8 for upper case "C." This code may be replaced with any appropriate code from the chart of FIG. 47. As shown in FIG. 22, a short time after the keys are depressed, the transducer outputs 310 are available. The keyboard strobe signal KBST 302 is generated. The Group A, B, and C pulses are supplied in bit parallel form to the input of the decoder 130 which is illustrated in FIG. 16. The decoder 130 is used in combination with the shift key 292 to indicate upper case. If the shift key was not depressed, the keyboard outputs would be supplied directly to the serializer 130 through the OR gates 312a through 312f of FIG. 17.

Referring to FIG. 16, the codes of Groups A, B, and C are decoded in such a manner that on the signals KSTK6 314 and KSTK67 316 are true for the above illustration. With these signals applied to the first vertical row 318 of AND gates from the left in FIG. 17, the lower AND gate 320 has a true output since KSTK67 316 and KBU8 are true; therefore, the output is also true. This output is supplied to the OR gate 324 and then inverted to supply a low signal at the AND gate 326 in the output section of the decoder 130 in FIG. 17. The other gates 312 in this vertical row will have an output which is characteristic of the keyboard output signals from FIG. 15.

In the serializer 132 shown in FIG. 17, the various AND gates 328a through 328g will provide an output according to the particular time of the gating signals WT7, WT0, WT1, WT2, WT3, WT4, and WT5. The serializer output KSER 304 is supplied to the keyboard buffer flip-flop 306 as shown in FIG. 14 which controls the transferring of information from the keyboard 120 to the keyboard buffer 134.

Information is loaded into the keyboard buffer 134 in character zero, CH0 328, and is removed therefrom from character two, CH2 330. Thus the keyboard buffer 134 must transfer the information from CH0 328 to CH1 332 and then to CH2 330. This allows first-in, first-out type of data transfer and also provides a buffer for the synchronizing of the speed of data handled by the terminal station 104 with the speed of data transmission which is slower. The transferring or shifting of information within the keyboard buffer 134 is controlled by the transfer control section 308 illustrated in FIG. 14 and shown in FIG. 18. The control comprises three flip-flops POFF 334, P1FF 336 and P2FF 338 which are identified as presence bit flip-flops. There is one flip-flop associated with each character of the keyboard buffer 134 and when that character is fully loaded, the corresponding flip-flop is set true. An additional flip-flop, the transfer flip-flop, XFRFF 340, is used as a one bit storage for the transferring of data from one character to the next.

As previously mentioned, the keyboard buffer 134 is a part of a 66-bit recirculating shift register. The shift register, since it is a recirculating device, has a single input and a single output. When the data in the keyboard buffer 134 must be shifted from stage 1 to stage 9 for instance, the output of stage 1 is read into the XFRFF 340 and stored until stage 9 has been effectively positioned at the input. At that time, the output of the XFRFF 340 is read into stage 9. To accomplish this operation, of the XFRFF 340 is read into stage 9. To accomplish this operation, the logic of FIG. 18 is used. When the information from the keyboard 120 has been fully loaded into CH0 328, the presence bit flip-flop POF 334 is set via an AND gate 342 as shown in FIG. 18. If the next character CH1 332 is full and CH2 330 is empty, three other AND gates 343, 344 and 346 in XFRFF control circuit will transfer the contents of CH1 to CH2 via XFRFF 340.

The information to be transferred is stored in XFRFF 340 for one word time plus one bit time as controlled by the FND bit 344 signal. The actual useful time is one character time since the keyboard buffer 134 effectively moves in the direction of the arrow 347 shown in FIG. 14.

The actual control of the transfer of information from the keyboard 120 to the keyboard buffer 134 is under the Keyboard State Machine which is diagrammatically shown in FIG. 19.

Keyboard State Machine

In FIG. 19, the state diagram for the transmission of information from the keyboard 120 to the keyboard buffer 134 is illustrated. The state machine is comprised of eight states which are identified by the status of three flip-flops, KSF1, KSF2, and KSF4. When power is applied to the terminal station 104, the initialized state KS0 348 is on and states KS1 through KS7 are off. The function of the several states are enumerated in the table below along with the status of the three flip-flops as shown in the Karnaugh map of FIG. 20.

State	Status	Function
KS0	000	Initial State.
KS1	001	4.55 ms delay.
KS2	010	Load CH0.
KS3	011	First delay after strobe.
KS4	100	Delay until WT0.
KS5	101	Write Presence bit.
KS6	110	Wait for end of strobe.
KS7	111	Not used.

Referring to the timing diagram of FIG. 22, the timing relationship between the several states of the Keyboard State Machine and the action of the keyboard 120 is plotted. The timing diagram is entered by the depression of a key from either keyboard 122 or 124. For the purpose of illustration, the depression is represented by a pulse 350 on FIG. 22. After a predetermined period of time, the key which has been depressed actuates a predetermined number of keyboard coded output slides. In the present embodiment there are seven slides which correspond to the 7-bit ASCII code as shown in FIG. 47. In order to insure an accurate read out from the transducers and to avoid any jitter, a keyboard strobing signal KBST 302 is generated to mask the transducer outputs 310. This window provides a stable time to sample each transducer. In the preferred embodiment, the transducers are magnetic cores and the window occurs after all switching transients have diminished.

Referring to the state diagram of FIG. 19, the indexing of the keyboard has occurred during KS0 348. When the keyboard strobing signal is true, the state machine progresses to KS4 352 on the first BT59 pulse which occurs.

The state machine remains in KS4 352 for the purpose of synchronizing the keyboard outputs with the basic timing of the terminal station 104. The signal to change from KS4 352 to KS2 354 is WT7-BT65 which will then place the beginning of KS2 coincident with WT0, CH0, CT0. With this synchronized beginning, it is easy to interrogate the transducers for each bit starting with the least significant bit 356 as shown in FIG. 47. The signal which is used to accomplish this task is shown generated in FIG. 18, and is FND BIT 344. The equation for the signal is as follows:

$$\text{FND BIT} = \text{WT0 CT0} + \text{WT1 CT1} + \text{WTn CTn}$$

where $n=0$ to 7.

Thus, for eight bit times in each word, the keyboard 120 may be searched. As shown in FIG. 14, this signal FND BIT 344 is gated via AND gate 358 with KS2 and CH0 to cause the output of KBDFF 306 to be read into the keyboard buffer 134. Therefore, when FND BIT is gated with CH0, only once each word is the keyboard buffer loaded with a bit from the keyboard. To further select which particular bit is to be generated from a particular transducer, the signal KSER 304 is generated at the outputs of one of seven AND gates 328a through 328g in FIG. 17 by WT1, WT2, etc.

After the last bit is decoded from the keyboard, the state machine progresses to KS5 360 at WT7-BT65. This state remains for only one clock time. During this state the presence bit flip-flop 334, POFF, is set indicating that the first character 328 of the keyboard buffer 134 is loaded.

The next state is KS6 362 which is another synchronizing state to allowing the signal KBST 302 to decay. The state machine remains in KS6 362 until the following signal sets state KS3 364:

$$\text{KS3} = \text{KBST} / \text{BT59}$$

States KS3 364 and the succeeding state KS1 366 provide a time delay in excess of 4.55 milliseconds. This is assured by the generation of a special keyboard clock KCLK 368 as shown in FIG. 21. The equation for the clock is as follows:

$$\text{KCLK} = \text{KCLFF WT0 CH0 CT0}$$

where KCLFF 370 is a modulus two binary counter counting WT7 pulses. Since one keyboard frame 172 equals eight words, the time between successive WT7's is 2.27 milliseconds.

The state machine remains in KS3 364 until KCLK 368 when the machine progresses to KS1 366. The time the

machine remains in KS3 varies but the state machine will remain in KS1 for the full 4.55 milliseconds as shown in FIG. 19.

On the next KCLK the state machine returns to KS0 to await the next keyboard operation.

The reason for the delay caused by states KS3 and KS1 is due to the use of magnetic core switching in the generation of KBST. After the time generated in KS3 and KS1, the magnetic cores have settled down and no false outputs will be generated.

Transmitted Data State Machine

When the terminal station 104 is operating on line, the information generated within the terminal station must be synchronized with the transmission frequency. This is accomplished in the Transmitted Data State Machine.

In FIG. 23 the state diagram for the transmission of data from the terminal station 104 to the central processor 100 is illustrated. The state machine is comprised of 8 states which are identified by the status of three flip-flops, TSF1, TSF2, TSF4.

When power is applied to the terminal station, the initialized state, TS0 is on and states TS1 through TS7 are off. The functions of the several states are enumerated in the table below along with the status of the four flip-flops as shown in the Karnaugh map of FIG. 24.

State	Flip flop status	Function
TS0	000	Initial State.
TS1	001	Read CH2 Loop 0.
TS2	010	Begin 2nd Stop Bit.
TS3	011	CH2 Loop 0 is a "1".
TS4	100	Begin 1st Stop Bit.
TS5	101	CH2 Loop 0 is a "0".
TS6	110	End of Data.
TS7	111	Process Data.

When the terminal station 104 is ready for transmission, a transmit enable signal, TEN, is generated and the information in the keyboard buffer 134, CH2 330, will be transmitted over the telephone lines 102 to the central processor 100. Referring to the timing waveforms of FIG. 27, there is illustrated the relationship between the several states. As hereinbefore mentioned, the frequency of the terminal station is 232 Hz. while the frequency of transmission is 120 Hz.; therefore, a special transmission clock, TCLK 372 must be generated which will synchronize the information in the terminal station with the transmission frequency.

FIG. 25 illustrates the combination of the logical elements used to generate TCLK 372 as defined by the following equation:

$$\text{TCLK} = \text{TCL1} \cdot \text{TCL2} \cdot \text{WT0} \cdot \text{CT0}$$

The two flip-flops, TCL1 374 and TCL2 376, are connected as a standard ripple counter of modulus 4. The counting signal for the counter is the end of

WT7 which occurs every 2.27 milliseconds; therefore, the period between each TCLK 372 is 9.09 milliseconds which is equivalent to 110 Baud. WT0, CH0, and CT0 are present in the equation to control the pulse width of TCLK 372 to 4.30 microseconds.

On the first TCLK after the transmit enable signal becomes true, the state machine progresses from TS0 378 to TS1 380. Simultaneously, on this TCLK pulse the transmit buffer 140, TBF, is reset to generate the start bit 382. Initially and at the end of each transmitted character, the status of TBF 140 is true which is equivalent to "mark."

The state machine remains in TS1 380 for a period of time sufficient to read the correct data bit for transmission from the keyboard buffer 134. Data transmission being in bit serial form, a transmission bit pointer 384 is used to indicate which bit is to be transmitted. The transmission bit pointer 384 is located in loop 1 CH2 and the point is a "1" bit which is shifted from bit position CT0 to CT7 as each data bit is transmitted.

The state machine remains in TS1 380 until loop 0, CH2 the output character of the keyboard buffer 134, is read. If the

output of loop 0 is true, the machine progresses to TS3 386; and if the output loop is false, the machine progresses to TS5 388. At the time the machine changes states from TS1 the present bit pointer is written into loop 1. In this instance, the bit pointer is written into loop 1. In this instance, the bit pointer is written into bit position 0 of character 2, loop 1.

The state machine remains in either TS3 or TS5 until the next TCLK pulse when the data bit is transferred to TBF 140 according to the state machine which is illustrated in FIG. 26. All data 1 pulses are also counted in a modulus 2 counter, TPF 390 of the parity generator 138, to determine parity.

The state machine remains in the next state, TS7 392, until the bit pointer is read from loop 1. When the bit pointer is read and the machine returns to TS1 380 and the present bit pointer is reset.

If at the time of reading the bit pointer in TS7 the bit counter is at CT6, the state machine does not return to TS1 but progresses to TS6 394. This indicates that the first seven data bits of the character in CH2 loop 0 have been transmitted and the parity bit must now be added in the eighth bit position. On the next TCLK pulse the output of TPF 390 is transferred to TBF 140 for transmission and the state machine progresses to TS4 396.

The next two states, TS4 396 and TS2 398, transmit the first and second stop bits for each character. Since the stop bit is a mark signal, TBF 140 is set true in TS4 396 and is not changed in TS2 398. The state machine remains in TS4 396 for one TCLK 372 pulse period and then remains in TS2 for the next succeeding TCLK pulse period. After TS2, the state machine returns to TS0 370 for the start of transmission of the next character.

When the character to be transmitted has been removed from the output character of the keyboard buffer 134 and the state machine progresses from TS6 to TS4, the keyboard presence flip-flop, P2F 338, is reset. The resetting of this flip-flop indicates that the output character 330 of keyboard buffer has been transmitted and the next character should be transferred into that character position. When P2F 338 is again true with the state machine in TS0, the transmission state machine will again begin the transmission of data to the central processor 100.

It is to be noted that while the output character 330 of the keyboard buffer is comprised of eight bits, only the first seven bits are used in transmission. The eighth bit is the Group C 296 or parity bit which is generated simultaneously as the character is transmitted and is inserted as the eighth data bit of transmission.

In summary, assuming the TCLK pulse which changes the state machine from TS0 to TS1 is the first TCLK pulse, then the following table will define the generation of a character with reference to TCLK and show the state of the state machine.

TCLK Pulse Number	State	Transmitted Data
1	TS0	Start Bit.
2	TS1, TS3+TS5, TS7	1st bit of data or least significant bit.
3-7	TS1, TS3+TS5, TS7	Next succeeding data bits in ascending bit value.
8	TS1, TS3+TS5, TS7	7th bit of data or most significant bit.
9	TS6	Parity bit.
10	TS4	1st stop bit (mark).
11	TS2	2nd stop bit (mark).
12	TS0	Start bit.

Received Data State Machine

In the block diagram of FIG. 3 line adapter 118 is shown connected to the incoming telephone lines 102 to receive information from the central processor 100. The line adapter 118 demodulates the signal level from the telephone lines 102 from ± 80 volts to ± 6 volts. The received data signals are further demodulated in the data level shifter 144 to the signal levels of the terminal station 104 which are $+5$ to 0 volts. Dur-

ing the time that information is not being transmitted, the signal level of the telephone lines 102 is at $+80$ volts or "mark." Likewise, at this time the output of the data level shifter 144 is $+5$ volts.

The Received Data State Machine is controlled by the condition of four flip-flops; namely, RSF1, RSF2, RSF4 and RSF8. The outputs of these flip-flops are gated to provide the several discrete decimal values from 0 to 15 which determine the particular state of the Received Data State Machine. The function of the several states are enumerated in the table below along with the status of the four flip-flops as shown in the Karnaugh map of FIG. 29.

State	Flip flop status	Function
RS0	0000	Initial state.
RS1	0001	1st 36 ms delay.
RS2	0010	36 ms delay.
RS3	0011	Do.
RS4	0100	End of character.
RS5	0101	Not used.
RS6	0110	Wait for start bit.
RS7	0111	Not used.
RS8	1000	First stop bit.
RS9	1001	Not used.
RS10	1010	Process data.
RS11	1011	Sample data.
RS12	1100	Second stop bit.
RS13	1101	Not used.
RS14	1110	Start bit received.
RS15	1111	Sampling timing.

When the terminal station is connected on line, the Received Data State Machine must determine the beginning of data reception. This is accomplished in states RS1 400, RS3 402, and RS2 404, as shown in the state diagram of FIG. 28.

As previously mentioned, the level of the telephone lines 102 during the period of no data is at the "mark" level and the output of the data level shifter 144 is $+5$ v. This output is applied to the received data flip-flop RCDF 146, setting the output of this flip-flop "true," or at $+5$ v. as shown in FIG. 30.

A transmission frequency of 110 bauds results in a transmission time of 100 milliseconds for one character of information. In order to determine the start character, the state machine determines that the state of RCDF 146 remains true for a period greater than 100 milliseconds. In the state diagram of FIG. 28, this is accomplished by utilizing the time periods generated by the sampling signal clock 406 as defined by the following equation:

$$SCLK = SCL1 \cdot SCL2 \cdot WT0 \cdot C^H0 \cdot CT0$$

Referring to FIG. 32, there is illustrated the logic elements necessary to generate the sampling signal clock, SCLK 406. The two flip-flops SCL1 408 and SCL2 410 comprise a modulus four counter to generate a SCLK signal every fourth WT7 time. Therefore, the output status of RCDF 146 is sampled every 36 milliseconds by SCLK 406.

In FIG. 28, upon applying power to the terminal station, the initializing routine sets the state machine to state zero, as identified by RS0 412. During the next three states, the state machine tests the output of the RCDF 146 to insure a valid start signal is being received. The state machine progresses from RS0 to RS1 during the first sampling time of the RCDF. While in RS1, if RCDF is reset, the state machine will return to RS0. The state machine remains in RS1 for a period of 36 milliseconds, as determined by the frequency of the sampling clocking pulse SCLK. It then progresses to RS3 for an additional 36 milliseconds, and then to RS2. Also while in RS3 or RS2, if RCDF is reset, the state machine will return to RS0. If RCDF 146 remains true during this period, which is greater than approximately 108 milliseconds, SCLK 406 will clock the state machine to RS6 413. The function of the three previously mentioned states is to synchronize the terminal station 104 with the signal received from the telephone lines 102.

The terminal station 104 will remain in RS6, fully synchronized with the line, until the start bit 414, which is a negative going signal from "mark" level to "space" level, as il-

Illustrated in FIG. 14, is received from the line and RCDF goes false, as illustrated in FIG. 34; and the terminal station progresses from RS6 413 to RS14 416. If, while the terminal station is in RS14, RCDF 146 goes true, this is considered a bad start condition and an error condition and the state machine will return to RS0 412.

In RS14 416, the logic of the terminal station is conditioned to generate a bit pointer signal which will be used in a succeeding state, RS11 418, for synchronizing the incoming data with its correct bit value. The received bit pointer 420 is stored in loop 1, character 3 of the recirculating shift register; and the received data is stored in the input buffer 150 in loop 0, character 3, as indicated in FIGS. 8 and 9. With the bit pointer in CT0, the incoming data bit will be inserted in CT0 of the input buffer likewise with the bit pointer in CT1, the incoming data bit will be inserted in CT1 of the input buffer, and so on as the receive bit pointer is progressively moved from CT0 to CT7. During RS14 416, positions CT1 to CT7 of the received bit pointer character are initially cleared.

Simultaneously upon progressing into RS14, which is accomplished by setting RSF8 421, the generation of the received data clock signal, RCLK 422, begins to synchronize the frequency of the received data with the frequency of the terminal station. FIG. 33 illustrates the combination of the logical elements used to generate RCLK 422, as defined by the following equation:

$$RCLK = RCLA / RCL1 \cdot RCL2 \cdot RCL4 \cdot RCL8 \cdot CH2 \cdot CT7$$

Five flip-flops RCLK to RCLA 424 through 428, are connected as a standard ripple counter of modulus 32. In order to have the first RCLK 422 pulse generated between the start pulse and the beginning of the first data pulse, the false output of RCLA 428 is used. The counting signal for the counter is basically BT65, which occurs every 283 microseconds; therefore, the first RCLK 422 pulse occurs 4.37 milliseconds after the start pulse 414, since the counter portion of the above equation is true on the fifteenth BT65 pulse and CH2 and CT7 occurs 31 bit times later, or CT7. Hereinafter, the counter portion of the equation will be true every 32nd BT65 pulse; and the time between successive pulses is 9.09 milliseconds.

When the first RCLK pulse 422 is generated, the state machine progresses from RS14 416 to RS15 430, where it remains until the next RCLK pulse which occurs at the middle of the first data position. On this pulse, the state machine progresses to RS11 418.

In RS11 418, the received bit pointer position 420 in character 3 of loop 1 is searched; and, upon receiving the signal therefrom, the machine progresses to RS10 432. During this switching time, the bit value of the input character is loaded into the input buffer 150, which is character position 3 of loop 0. If RCDF 146 is false at this time, a "0" will be loaded into loop 0 character 3; and, conversely, if RCDF 146 is true, a "1" will be loaded. Since this is the first pulse, the state machine leaves RS11 418 at CT0 and progresses as to RS10 432 at CT1. While in RS10 the new received bit pointer is entered into loop 1, character 3. The state machine then returns to RS15 430 and waits for the next RCLK 422.

After loading the eighth bit of received information into the input buffer 150 in RS11 418 and the state machine progresses to RS10, the bit counter is at CT0 and the state machine does not return to RS15 but progresses to RS8 434. During RS8 the state machine tests the character of the stop bit part of the message. The stop bit is a mark signal, and therefore, the status of the RCDF flip-flop 146 must be true. The RCDF flip-flop is sampled at the next succeeding RCLK pulse; and if the flip-flop is still true, the state machine progresses to RS12 436, indicating that the first stop bit is at mark. If RCDF is false, the state machine returns to RS0 412, indicating that the first stop pulse is bad and that the terminal station 104 must be resynchronized with the line.

With the first stop bit at mark, the state machine progresses to RS12, where the same test is performed on the second stop

bit. If, during the next RCLK, the second stop bit is at mark, the state machine progresses to RS4 438. If the second stop bit is at space, RCDF is false; and the state machine is returned to RS0 to resynchronize the terminal station with the line. Since, by the logic equation, the RCLK pulse always occurs at character 2, bit 7, CH2-CT7, which is the 31st pulse, the state machine remains in RS4 until bit time 64, when we set the received data presence bit 440 in loop 0, bit position 64. The state machine is then returned to RS6 413, ready for the next start bit. The received data presence bit 440 will be used to transfer the information from the input buffer 150 into the C register 154 for additional processing.

Received Data Parity Check

After the input buffer 150 is loaded with a character of information and the received data presence bit 440 is written in BT64 of loop 0, the contents of the input buffer 150 may be an alpha character which is encoded in the 7-bit ASCII code or the character may be a numeric character which is encoded in an 8-bit modified Hamming code. The 8-bit modified Hamming code contains four information bits or Group B bits 294 and Group C bits 296 which when taken in a predetermined combination can determine with a high degree of accuracy the correctness of a numeric character. The table below illustrates the four combinations of information bits and group parity bits which are checked in each Hamming character:

30	Information Bits				Group Parity Bits			Character Bits
	Group A				Group B			
	CT3	CT2	CT1	CT0	CT6	CT5	CT4	CT7
	X	X	X	-----	-----	X	-----	-----
	X	-----	-----	X	X	-----	-----	X
	-----	X	X	X	X	-----	-----	-----

35 The ASCII character is checked at one time by checking all seven information bits plus the parity bit for an even parity condition. FIG. 36 shows the logical elements which are used for parity checking the information in the input buffer. FIG. 35 is a modified state machine diagram for parity checking.

40 When the last bit of a character is loaded into the input buffer 150 and the Received Data State Machine progresses to RS4 438, the received presence bit 440 is loaded in BT64 of loop 0. During WT3, BT64, loop 0 is read and the Decode State Machine is initiated by the data presence bit 440 setting the state machine to DS7 272 from DS0 270 for the start of parity check. At the same time, the keyboard-line flip-flop 278, KF, is reset for purposes which will be explained later.

45 As shown in FIG. 8, the BT65 of loop 0 is the error flag position 442 of the shift register. If this position contains a "1," then the terminal station 104 would be switched to an error routine; and conversely, if this position contains a "0," the terminal station remains in a nonerror state. On the next basic timing pulse 178 after DS7 272 is reached, which is BT65, this error flag is set to "0" prior to checking for parity. If this position had a "1" at this time, the error condition would have been cleared prior to data reception by the terminal station.

50 During DS7 272, the input buffer is read during each of the next four word times; namely, WT4, WT5, WT6, and WT7. As shown by the signals on the AND gate 444 in FIG. 36, only during CH3, which is the input buffer, are the pulses from loop 0 counted by the Receive Parity Flip-Flop 446, RPF.

55 In FIG. 36, the four AND gates comprising the Hamming timing window 448 and the single AND gate which comprises the ASCII timing window 450 are shown. These two sets of gates are controlled by the status of the Hamming flip-flop 452, HF, illustrated in FIG. 40. The signal LSES01 454 indicates that the information being checked was received by the terminal station 104 from the central processor 100.

60 A subroutine is shown in FIG. 35 having steps EC1 through EC4 455 through 458 which are followed to check each of the four group parity bits in the Hamming code. This routine checks the complete ASCII character in each subroutine state but as will be shown, only the character check performed in step EC4 458 is noted.

During each of the first three steps of the subroutine; namely, EC1 455, EC2 456, and EC3 457, the error flag in loop 0 BT65 will be set if there is a parity error detected and the character being checked is a Hamming character. The flag is set according to the following equation:

$$\text{ERROR} = \text{BT65} \cdot \text{HF RPF}/$$

During each step of the subroutine, the summation of the data pulses must be odd and at BT65, the status of RPF 446 must be true or the error flag is set.

If the character being checked is an ASCII character, the summation of all of the data pulses must be even and the status of RPF must be false.

At the end of the fourth check of CH3, in step EC4 458, the following BT65 pulse changes the Decode State Machine to DS3 276 for transferring the contents of the input buffer 150 to the C register 154 for processing or to DS0 because of a parity error. The equation for parity error being:

$$\text{PERR} = (\text{LOR} + \text{HF RPF}/ + \text{HF RPF}) \text{ BT65}$$

The first term, LOR, is the output of loop 0 sampled at BT65 which is the error flag position. If a Hamming parity error was found during EC1, EC2, or EC3, the flag would have been set and LOR would be true. The second term, HF RPF/, is the Hamming parity error check. If an error occurs at this time, the error flag is also set in loop 0 BT65. The third and last terms, HF RPF, relates to the parity check of an ASCII character made during EC4.

If the received data character is free of parity errors, the Decode State Machine progresses to DS3 276 wherein the contents of the input buffer 150 are transferred to the C register 154.

C Register

After the received data has been checked for parity, the Decode State Machine progresses to DS3 wherein the contents of the input buffer 150 are transferred to the C register 154 for decoding.

The C register 154, as illustrated in FIG. 40 comprises eight JK flip-flops C7F—C0F connected as a conventional shift register. C7F contains the most significant bit of the character stored in the C register. The information is transferred in serial form from the input buffer via a four-input AND gate 460 into C7F. The first input to the AND gate 460 is the data line from the input buffer 150, the second input line identifies the particular bit position of the input buffer, the third input identifies the character position of the input buffer in the loop which is character 3 and the fourth input identifies the state machine state, DS3.

As each bit is transferred from the input buffer 150, the C register 154 is shifted by shift control gate 462 wherein the basic timing pulse T is gated with character time. After the C register is fully loaded with the information from the input buffer 150, the Decode State Machine progresses to DS2 280 according to the following equation:

$$\text{DS2} = \text{DS3} \cdot \text{CH5bq} \cdot \text{CT7}$$

In DS2 280, the C register 154 is decoded in the decoder 156 and the decoded signals are applied to the control matrix 158. As illustrated in FIG. 40, the first three stages of the C register; namely, C0F, C1F and C2F are decoded into eight discrete signals identified by CD0 through CD7 in a binary to octal decoder. The fourth stage is not decoded and preserves its data value through the C register decoder 156. The last three stages, C5F, C6F and C7F are decoded and provide three signals which represent particular control "sticks" for the identification of functions. These signals are CSTK0, CSTK1 and CSTK67.

In the control matrix 158, the above enumerated signals are discretely gated to provide several control signals used to control the terminal station 104. As an illustration in FIG. 40, there are three particular signals which are defined by the following equations:

$S \leftarrow \text{CD6} \cdot \text{C3F} \cdot \text{CSTK0}$

$SI \leftarrow \text{CD7} \cdot \text{C3F} \cdot \text{CTSK0}$

$POS = HF \cdot S \#$

All three signals $S \#$ 464, SI 466, and POS 468, are signals which are received by the terminal station from the central processor 100. The signal $S \#$ 464 indicates that all subsequent characters to be received by the terminal station will be numeric digits and in the Hamming code. The signal POS 468, is a printer command indicating that the printer element 160 will be moved to a new POSition which will be identified by the next two characters. SI 466 is a signal indicating that all subsequent characters will be alpha characters and in the ASCII code.

At the end of the decoding time, the state machine progresses from DS2 280, or preeexecute state, to DS6 284, or execute state, according to the following equation:

$$20 \quad DS6 = DS2 \cdot CH5bq \cdot CT7 \cdot KF/$$

The signal KF/ is the "0" output of the keyboard line flip-flop 278 shown in FIG. 37 and indicates that the commands to be processed are from the central processor 100.

In state DS6 284 the commands as illustrated in FIG. 41, are executed according to their respective functions. The signal $S \#$ 464 is applied to the Hamming flip-flop 452, HF, to set this control member to open the Hamming parity check window 448 in FIG. 36. It is the status of this control member 452, HFFF, which determines the mode of parity checking of incoming signals. The timing signal which is generated to trigger this flip-flop is CXTT 469 which is defined as follows:

$$35 \quad CXTT = DS6ch \cdot BT65 \cdot WT7 \cdot ENCXT$$

If the prior received command was $S \#$ 464 and this command is POS 468, the signal POSXT 470 is generated by the AND gate 472 which defines POSXT as follows:

$$40 \quad POSXT = HF \cdot S \# \cdot CXTT$$

The signal POSXT will cause the terminal station to initiate another state machine which is the Position Code State Machine.

If the received command is decoded as SI 466 the signal CXTT 469 will reset the Hamming flip-flop 452 which will close the Hamming parity check window 448 and open the ASCII parity check window 450 shown in FIG. 36. This signal indicates that all subsequent commands are in the ASCII code and only a signal parity check need be made on each received character.

With any of the above enumerated commands, the Decode State Machine progresses from DS6 284 to DS0 270 according to the following equation:

$$55 \quad DS0 = DS6 \cdot BT65 \cdot WT7$$

This state machine remains in DS0 until the next character is fully loaded into the input buffer 150 and the data presence bit 440, BT64 of loop 0 is read and the state machine goes to DS7 272 for receive parity check.

Position Code State Machine

As previously mentioned in connection with FIG. 40, if the command received by the terminal station 104 from the central processor 100 is decoded as POS 468 during DS2, this signifies that the subsequent characters to be received by the terminal station will indicate a new printer 160 position. In DS6 284 the command execute signal CXTT 469 is generated and when combined with POS generates position execute POSXT 470 which initiates the Position Code State Machine.

In FIG. 41 there is shown the data flow of the next two characters following the POS command in conjunction with the state diagram for the Position Code State Machine. The state machine is comprised of four states which are identified

by the status of two flip-flops PMF1 and PMF2. When the power is applied to the terminal station, the initialized state PM0 is on and states PM1, PM2, and PM3 are off. The functions of the four states are enumerated in the table below along with the status of the two flip-flops shown in the Karnaugh map of FIG. 42:

State	Status	Function
PM0.....	00	Initialize.
PM1.....	01	Load least significant digits.
PM2.....	10	Execute.
PM3.....	11	Load most significant digits.

When the terminal station 104 is in DS6 284 and the command which is received is POS 468, the Position Code State Machine progresses from its initialized state, PM0 474, to state PM1 476. The Position Code State Machine remains in state PM1 476 until such time as the next character, which is being received from the central processor 100, has been loaded into the C register 154 and the Decode State Machine progresses to DS2 280. Since the character is a Hamming character, the first four stages of the C register; namely, COF through C3F contain the least significant four bits of the printer position. The upper four stages of the C register contain the Hamming group parity bits 294 which will be disregarded during this operation. The Decode State Machine remains in state DS2 280 for one word time beginning with CH6 CT0 and ending with CH5 CT7. Concurrently, the Position Code State Machine for the first character immediately following a position command is in state PM1 476. It is the function of state PM1 to transfer the information in the C register 154 to the desired position register 478 which is loop 1 character 5. This operation takes place during CH5 time of DS2.

As shown in FIG. 41, the transfer of information from the C register 154 to the desired position register 478 is a serial operation from COF of the C register. The data flow is controlled by a 4-input AND gate 480 where the first input is connected to COF, the second input identifies the particular state machine times; namely, DS2 and PM1; the third input identifies the character times; namely, CH5; and the fourth input identifies the bit times; namely, CT4f/.

When the Decode State Machine progresses through DS2 to CH5, the data transfer operation from the C register 154 to the desired position register 478, character 5 loop 1, begins. As previously mentioned, this is a Hamming character and only the first four positions of the C register 154 will be transferred. With the Position Code State Machine in state PM1 476, the data to be transferred comprises the least significant bits of the position number. Therefore, the AND gate 480 is open during time CT0 through CT3.

The Position Code State Machine remains in state PM1 until the Decode State Machine returns to DS0 from DS6. At that time, the Position Code State machine progresses to state PM3 482.

The operation of state PM3 482 is identical to the operation of state PM1 476 with the exception that the character in the C register 154 is the most significant four bits of the new position register. During DS2 and PM3 time, a second AND gate 484 is opened during the last four bit times of character 5 as identified by the signal CT4 F. This signal allows the transfer of the four bits in the C register 154 stages CT0 and CT3 to the upper four bit positions of the desired position register 478, character 5 of loop 1. The Position Code State Machine remains in state PM3 482 until the end of state DS6 when the Position Code State Machine progresses to PM2 486 the Decode State Machine progresses to DS4 for the execution of the printer movement according to the command received.

When the printing element 160 has received the position identified in the desired position register, the signal SY40 is generated which indicates completion of the command and returns the Position Code State Machine to state PM0 74 as indicated by the AND gate 488 in FIG. 41.

Interrupt State Machine

In the block diagram of FIG. 3, the interrupt key is illustrated by the box labeled Interrupt 490. The output of this key is connected to the keyboard buffer via conductor 492. This illustrates that the signal generated by the interrupt key will be transmitted by the terminal station 104 to the central processor 100.

The Interrupt State Machine is diagrammed in FIG. 43. The machine is controlled by the condition of two flip-flops; namely, ISF1 and ISF2. The outputs of these two flip-flops are gated to provide the four states of the interrupt state diagram. The function of the four states are enumerated in the table below along with the status of the two flip-flops as shown in the Karnaugh map of FIG. 44.

State	Flip flop status	Function
IS0.....	00	Initial State.
IS1.....	01	Wait for keyboard buffer to empty.
IS2.....	10	Wait for start of transmission.
IS3.....	11	Load interrupt code into keyboard buffer.

When the terminal station 104 is connected to a source of power and turned on, the initializing routine of the station sets the state machine to state zero, as identified by IS0 494. The machine remains in this state until the interrupt key 490 is depressed when the terminal station 104 is in the on line unattended mode. The equation for progressing from IS0 to IS1 is:

$$IS1=INTRPT\cdot CH0\cdot CT7\cdot (IP2F+ONLU)$$

where

INTRPT = Output from interrupt key

ONLU = On line unattended

When the state machine progresses to IS1 496, the machine remains in that state until the keyboard buffer 134 is empty. This allows the present operation of terminal station 104 to complete its transmission to the central processor. When the keyboard buffer 134 is empty the three presence bit flip-flops, P0FF 334, P1FF 336 and P2FF 338 are reset generating the signal PSO according to the following equation:

$$PSO=P0FF\cdot P1FF\cdot P2FF\cdot$$

Also, the other state machines must be in their initialized state, thus safeguarding against interruptions into desired operations.

The central processor 100 must receive a signal indicating that the operation of the terminal station 104 is being interrupted. This signal is generated in state IS3 498. The state machine progresses from IS1 to IS3 when the previously mentioned conditions are met and the basic machine timing is at BT65.

In IS3, the interrupt code is loaded into the keyboard buffer 134 at loop 0 CH0. The code, from most significant bit to least significant bit is:

$$INTCODE=00010100$$

When the basic timing progresses to WT7-BT65, the state machine progresses to IS2 500, where it remains until the interrupt code, INTCODE, is being transmitted by the transmit state machine at which time the state machine returns to IS0 494.

When the central processor 100 receives the INTCODE, it will then transmit to the terminal station an acknowledgement which will turn off the on line unattended indicator. Thus the operator is informed by visual means when she has regained control of the terminal station. At this point in time the terminal station is still on line with the central processor but by subsequent depression of the type program select key, the operator can go off-line.

In summary, there is shown and described a terminal station for communicating with a central processor via telephone lines. The terminal station has an alpha keyboard and a numeric keyboard which is adapted to generate a positionably

coded signal for each key thereon. The numeric codes, being the same as several of the alpha codes, is distinguished therefrom by either of two particular coded signals which indicate the codal format of transmission. A recirculating memory provides a time sharing storage member capable of substantially simultaneously handling information being received by the terminal station, information being transmitted by the terminal station, and information being processed by the terminal station. The keyboard is capable of generating a plurality of groups of codes wherein each codal group or groups represents information, group parity or line parity.

We claim:

1. In an on line data communication system having a multimode terminal station operatively connected via a communication channel to a central processor and controlled thereby, said terminal station comprising:
  - a keyboard having an alphabetic section and a numeric section for entering new data into the communication channel;
  - said alphabetic section having means to generate a codal representation of each of said alphabetic characters, said representation comprising seven data bits;
  - said numeric section having means to generate a codal representation of each of said numeric characters, said representation comprising four data bits and three parity bits;
  - transmission means operatively coupled to said keyboard to transmit said new data from said keyboard to the central processor over the communication channel;
  - first synchronizing means to synchronize the frequency of said new data with the frequency of the communication channel;
  - parity generation means operatively coupled to said transmission means and responsive to said first synchronizing means to generate a parity bit according to the codal representation of the seven bits from each of said keyboard sections;
  - receiver means operatively coupled to the communication channel to receive data comprising seven data bits and one parity bit from the central processor;
  - second synchronizing means to synchronize the frequency of said received data with the frequency of the terminal station;
  - first parity checking means operatively coupled to said receiver means and responsive to said second synchronizing means to generate a parity bit in response to each alphabetic character;
  - second parity checking means operatively coupled to said receiver means and responsive to said second synchronizing means to generate a parity bit in response to each numeric character;
  - comparator means operatively coupled to said first and said second parity checking means and responsive thereto to compare the generated parity bit with the received parity bit; and
  - recirculating storage means responsive to said first synchronizing means and operatively coupled to said keyboard means for storing said new data and simultaneously responsive to said second synchronizing means and said comparator means and operatively coupled to said receiver means for storing said received data.
2. A device for generating electrical signals to be transmitted via a communication line, said device comprising:
  - first keyboard means for generating coded signals in accordance with a first coding format for alphabetic information;

second keyboard means for generating coded signals in accordance with a second coding format for numeric information, each of said first and second coding formats having a like number "n" of binary bits for each character of its information type, all of said "n" bits of said first coding format representing information bits of an alphabetic character and a first group of "x" bits of said second coding format representing information bits of a numeric character and a second group of "n-x" bits representing parity bits, said parity bits correlating with the bits of said first group of "x" bits; and

first and second switch means operatively connected to said first and second keyboard means respectively and selectively operable to generate a first electrical signal indicating said first coding format represents an alphabetic character and a second electrical signal indicating said second coding format represents a numeric character.

3. The terminal device as defined in claim 2 additionally including means for adding at least one additional parity bit to form a (n+1) bit coded signal for each character of both the alphabetic and the numeric information.

4. The device defined in claim 2 wherein said number "n" equals seven and the number "x" equals four.

5. In an online data communication system having a multimode terminal station operatively connected via a communication channel to a central processor, the multimode terminal station comprising:

a keyboard having a plurality of data and operational keys thereon to generate positionably coded signals representing alphabetic and numeric characters and operational instructions in response to the operation thereof;

a printer to print alphabetic and numeric characters at the terminal station;

a printer buffer operatively connected to said printer to receive and store the alphabetic and numeric characters to be printed;

transmission means for transmitting said positionably coded signals over the communication channel;

reception means for receiving said positionably coded signals from the communication channel;

mode selection means to select the operational mode of the terminal station; and

recirculating storage means operatively connected to receive the positionable coded signals representing alphabetic and numeric characters from said keyboard and said reception means and to couple said signals to said transmission means and said printer buffer in response to said mode selection means.

6. The multimode terminal station according to claim 5 wherein said mode selection means comprises in combination at least two flip-flops responsive to said operational keys on said keyboard to select one of three modes of operation wherein the normal mode of operation operatively couples the terminal station to the communication channel for the transmission of positionably coded signals from said keyboard.

When the terminal station 104 is connected to a source of power and turned on, the initializing routine of the station sets the state machine to state zero, as identified by ISO 494. The machine remains in this state until the interrupt key 490 is depressed when the terminal station 104 is in the on line unattended mode. The equation for progressing from ISO to IS1 is:

$$IS1=INTRPT.CH0.CT7.(IP2F +only)$$

where

INTRPT =Output from interrupt key
only =On line unattended

UNITED STATES PATENT OFFICE
CERTIFICATE OF CORRECTION

Patent No. 3,588,834

Dated June 28, 1971

Inventor(s) John H. Pedersen, Michael M. Malmer, Jr.,
Charles B. Hebeler, and Hoy Ying Chang

It is certified that error appears in the above-identified patent
and that said Letters Patent are hereby corrected as shown below:

- Col. 8, line 20, should be "TCF = CT7/.TUF/
- Col. 8, line 59, should be "10 depict the organization".
- Col. 16, line 44, should be --232 KHz".
- Col. 16, line 45, should be "110 Hz".
- Col. 16, line 53, should be "CHO.CTO".
- Col. 20, line 20, after "or" and before "Group B" insert
                          --Group A bits 298 and four group parity
                          bits or--.
- Col. 20, line 49, should be "contains a "1",".
- Col. 21, line 58, should be "CH5. CT7".
- Col. 22, line 21, should be "CH5. CT7. KF/".
- Col. 22, line 35, should be "DS6. BT65. WT7. ENCXT".
- Col. 23, line 75, should be "PMO 474".

Signed and sealed this 14th day of March 1972.
